UNITED STATES PATENT OFFICE

NICKOLAS MEROUSSIS, OF NEW YORK, N. Y.

SWIMMING APPLIANCE

Application filed April 25, 1930. Serial No. 447,260.

This invention relates to swimming appliances and has for an object the provision of a simply constructed and effective device which will make swimming easier and more enjoyable to those who wear it. With the above and other objects in view, the invention further includes the following novel features and details of construction to be fully described and illustrated in the accompanying drawings and the appended claims.

In the drawings:

Figure 1 illustrates a swimmer equipped with my improved swimming appliance and its parts in sections.

Figure 2 is a perspective view showing a swimmer from the side, wearing the swimming appliance shown in Figure 1 and in the act of swimming; and

Figure 3 is a rear view of the swimmer wearing the appliance of my invention and in the act of swimming.

Referring to the drawings for a more detailed description thereof, the numeral 5 indicates a triangular web positioned between the legs as clearly shown in Figures 1 and 3. This web is secured to the legs of the swimmer by means of holding members 7 each comprising front straps 8 and rear straps 9 which are secured together by means of buckles 10, the straps 8 and 9 encircling the legs of the swimmer.

The triangle 5 is secured to a body portion 12 by means of divergent straps 14 which are secured by means of buckles 15 to straps 16 depending from the lower edge of the body portion 12. The body portion 12 may be made of any suitable material such for example as canvas but it is preferably made of a flexible water-proof material such for example as rubberized cloth. The portion 12 is fastened by buckles 12a.

The body portion 12 has extending from the upper edge of its front portion a pair of straps 18 which are secured by means of buckles 19 to respective members of a pair of straps 20 which run over the shoulders of the swimmer and are secured to the upper edge of the back portion of the body member 12. Secured to the respective sides of the body member 12 are a pair of triangular

webs 22, one between each arm and the swimmer's body. The webs 22 are secured to the arms of the swimmer by means of fastening members 24, each of which has front straps 25 and rear straps 26, the front and rear straps being secured together by means of buckles 27. The webs 22 are secured to the body member 12 along the lines 30, which it will be noted are a little to the front of the side of the body. When thus attached the webs 22 extend backwardly about fifteen degrees to the arms. This disposition of the webs is suitable for ordinary swimming. However if the backstroke is to be used in swimming the webs are to be reversely inclined. That is to say, the lines of attachment of the webs to the body member will be slightly back of the side of the body member or in other words back of the dotted lines 32 which indicate the side of the body.

While my appliance is shown and described as a two piece device, it is to be understood that it can be united by cloth or canvas and serve as a swimming suit without departing from the invention.

To enhance the folding and unfolding movements of the web, resilient reinforcing elements may be used such as resilient blades arranged or molded in the web in such a way that will allow the folding and unfolding of the web.

From the above it is apparent that this device will give to the swimmer the means a fish has. Lifting the arms parallel to the body to a distance allowed by the triangle webs 22, opening one elbow at the right and the other elbow at the left at an angle to the body and making fast backward movement of the arms and feet from a bended position of the body, will result in a powerful forward propelling force with less effort than will be required of a swimmer not wearing my device, as my appliance involves simply the movement of the elbows and not the full extension of the arms as applied to ordinary swimming.

From the foregoing the advantages and novel features of the invention will be readily apparent.

What I claim is:

1. A swimming appliance comprising a body portion, a pair of webs, one under each arm, secured to said body portion, and means for securing said webs to the arms, said webs being secured to said body portion at an angle to the body.
2. A swimming appliance comprising a body portion, a pair of webs, one under each arm, secured to said body portion, and means for securing said webs to the arms, said webs being secured to said body portion at an angle of about 15 degrees to the body.
3. A swimming appliance comprising a body portion, a pair of webs, one under each arm, secured to said body portion, means for securing said webs to the arms, said webs being secured to said body portion at an angle to the body, a web between the legs, means for securing the last mentioned web to the legs and means for securing the last mentioned web to the body portion.
4. A swimming appliance comprising a body portion, a pair of webs, one under each arms, secured to said body portion, means for securing said webs to the arms, said webs being secured to said body portion at an angle of about 15 degrees to the body, a web between the legs, means for securing the last mentioned web to the legs and means for securing the last mentioned web to the body portion.
5. A swimming appliance comprising a body portion, a pair of webs, one under each arm, secured to said body portion, means for securing said webs to the arms, said webs being secured to said body portion at an angle to the body, and shoulder straps for holding said body portion.

40 In testimony herein I affix my signature.

NICKOLAS MEROUSSIS.
